GARMENT FASTENING DEVICE

Benjamin Liebowitz, New York, N. Y., assignor to
 S. Liebovitz & Sons, Inc., New York, N. Y., a
 corporation of New York

Application November 22, 1932, Serial No. 643,827

8 Claims. (Cl. 1-3)

This invention relates to a garment fastening device, and more particularly to a device for stapling folded portions of a garment, such as a shirt or the like.

In folding shirts at the factory or laundry, it has been the practice to use a multiplicity of pins to fasten the folded portions, the pins being successively applied in a series of separate operations. This separate securement of independent pins is objectionable not only because it is time and labor consuming, but also because the purchaser of the shirt is compelled to search laboriously for and remove the pins, which latter are apt to prick and injure the fingers both of the person applying as well as the person removing the pins.

The present invention aims not only to avoid the use of a multiplicity of separate pins, but to provide a device whereby the folded parts of a garment may be easily and quickly fastened by means of staples which penetrate the folded portions and are removable as a unit to release the folded portions by a single movement of the fastener.

The invention comprises the novel features of construction, arrangement and combination of parts hereinafter fully described and illustrated in the accompanying drawings, in which:

Figure 1 is a plan view of the folding board and stapling head, showing the latter in one of its neutral or out-of-operation positions;

Fig. 2 is a plan view of the same, with a shirt folded on the board and the stapling head in one of its staple-driving positions;

Fig. 3 is a vertical section, on an enlarged scale, taken on the line 3-3 of Fig. 2, the folded portions of the shirt being indicated diagrammatically by dot and dash lines;

Fig. 4 is a detailed side view, partly in section, showing the clamping arms raised and the stapling head in neutral position;

Fig. 5 is a detailed view, partly in section, showing the clamping arms depressed and the staple-driving head in one of its staple-driving positions;

Fig. 6 is a detailed fragmentary plan view of the stapling head mounting with the stapling head removed; and

Fig. 7 is a detailed view of the fastener showing the staples in secured position, the folded fastened portions of the garment being indicated diagrammatically by the dot and dash lines.

Referring now to the drawings, 1 is a rectangular board or plate around which the shirt 2 or like garment is folded and on which the parts to

be fastened are positioned substantially as shown in Fig. 2. The folding board may be provided at its upper corners with clips 3 to hold the cuffs in place, and with notches along the upper and lower edges to facilitate centering the board in respect to the shirt.

4 indicates generally a stapling head, preferably of the type having a reciprocal staple-driver. The stapling head is conventional and I make no claim thereto except in relation to the elements herein described.

The stapling head is pivoted at 5 in a supporting arm or bracket 6 to swing vertically on the pivot. The arm 6 itself is mounted to swing horizontally through an arc so that the stapling head may be swung bodily from its neutral or out of the way positions into operative or stapling relation with the anvils or clincher blocks 7 against which the staples are driven. In Figure 1 the stapling head is shown in one of its neutral positions, while Fig. 2 shows it in one of its staple-driving positions.

Suitable indexing means may be provided to indicate the several positions of the stapling head. These means, as best seen in Fig. 5, may comprise a pin 8 having a conical point 9 and movable vertically in the hole 10 in the supporting arm. The stapling head carries a pin 11 which is pressed downwardly on the pin 8 by the spring 12. On swinging the stapling head horizontally, the point of the pin 8 engages in one or the other of the index holes 13 and 14, which holes are disposed in the base plate 15 in spaced semi-circular arrangement. Contact of the point of the pin with either of the index holes 13 indicate stapling positions of the head, while contact with the holes 14 indicate neutral positions.

Means also may be provided to hold the stapling head in accurate registration with clincher blocks or anvils 7 during the staple-driving operation. To this end I may provide a pin 16 having an enlarged head 17 which seats on the spring 18 housed in counterbore 19 in the supporting arm. When the stapling head is swung vertically downwards as shown in Fig. 5, the lower surface of the head bears down on the pin 16 and forces it into the hole 20, thus holding the stapling head against horizontal displacement.

Both the stapling head 4 and the anvils 7 are preferably carried on the base plate 15, which plate is detachably secured to the underside of the folding board 1 so that the stapling assembly may be detached conveniently as a unit and applied to other boards of different size or shape. It will be seen that the anvils 7 extend upward

from the base plate 15 through slots or openings 21 in both the board and the plate 22 mounted on the upper surface of the board, the anvils being preferably mounted to permit of adjusting their positions on the base 15.

23 is a pedestal fixed immovably to the base plate. It will be seen on referring to Fig. 5 that the base of this pedestal is the axis around which the arm or bracket 6 swings. A pair of arms 24 and 25 are pivoted at opposite points 42 on the pedestal to swing vertically as indicated in Fig. 4. The outer extremity of the arm 25 carries a clamping finger 26 for the purpose hereinafter described. Extending transversely across the outer ends of the arms 24, 25 is a stud bolt 27 upon which an arm 28 is mounted to swing or revolve independently of the swinging movement of the arms 24—25. The outer end of this arm is in the form of an open frame 29 (see Fig. 2) and may be provided with a handle knob 30.

Means are provided to press both the finger 26 and the arm 28 downward when these parts are lowered into their clamping positions as shown in Fig. 5, said means serving also to hold both arms stable when they are swung upward into their raised positions, shown in Fig. 4. These means preferably comprise a curved-end block 31 carrying a forwardly extending hollow sleeve 32, said block being pivoted at 33 between a pair of ears 34 on the pedestal 23. A rod 35 slides lengthwise in the bore of the sleeve 32. The head 36 of this rod is pivoted at 37 to turn between the ears 33 on the inner end of the arm 28. These ears extend at an angle to the plane of the arm 28. A helical spring 39 encircles the sleeve 32 and rod 35, and bears at its ends against the parts 31 and 36, respectively. It will be noted that when the parts are in the positions shown in Fig. 5, the center of the pivot 33 lies in a slightly higher horizontal plane than the center of the arms 24—25, and consequently the spring 39 exerts a downward pressure or thrust on the arm assembly. When, however, the parts are swung into their raised positions shown in Fig. 4, the forward edge 40 of the plate 41 serves as a stop to limit the upward movement of the arms 24—25. It will be observed that in this position the center of the pivot 33 is below the longitudinal center line of the arms, and that therefore the spring exerts an upward thrust acting to hold the arms stable in this position. The arm 28 is likewise held at rest in its raised position by the upward thrust of the spring.

In use, the shirt 2 is laid bosom down on a flat table. The folding board 1 with the clamping arms in their raised positions as shown in Fig. 4, is placed on the back of the shirt with the upper edge of the board lined with the upper edge of the collar and with the board centered transversely of the shirt. The notches in the upper and lower edges of the board facilitate proper placing of the board relative to the shirt.

A strip of paper 43 or like flexible material is laid on the plate 22 in between the guides 44. The sides of the shirt are now folded over the sides of the board, and the cuffs, in the case where the cuffs are to be folded on the back, are engaged in the clips 3. In the folding operation the shoulder portions of the shirt are folded inwardly, over the anvils 7, and preferably in overlapping relation. The arms 24—25 are then swung downwardly so that the finger 26 will clamp said portions in their folded position. It is to be noted that when the arms 24—25 are swung downwardly the independent movable arm 28 is

still in raised position relative to the first mentioned arms. The skirt of the shirt is now folded over the lower edge of the board and the arm 28 is then swung down on the skirt to clamp it in position.

A second strip of paper 45 or like material is placed in the opening of the frame 29, over the skirt. The stapling head 4 is then swung into one of its stapling positions, as shown in Fig. 2, and the staple driver is pressed down to drive a staple 46 through the strips 45—43, and through the intervening folded portions of the shirt.

On referring particularly to Fig. 6, it will be seen that the grooves 47 in the anvils 7 are so formed as to bend both prongs or points of each of the staples 46 outwardly, that is, towards the adjacent side edge of the board. The stapling head is then swung into its second stapling position and a second staple 46 is driven through the opposite ends of the strips 45—43. The arm 28 is then swung upwardly and the folded, stapled shirt is slid off the board.

All of the folded, fastened portions of the shirt are securely held together by means of the two staples as indicated diagrammatically in Fig. 7. In this figure it is to be noted that both of the bent under prongs of each staple extend in the same direction and oppositely from those of the other staple. In order to unfasten all of the parts, it is merely necessary to engage the upper paper strip 45 and to pull the strip upwardly thus withdrawing and disengaging the staples, and thus by a single operation releasing all of the folded parts simultaneously.

It is to be understood that various modifications in the construction and arrangement of the parts herein illustrated and described may be made without departing from the scope or spirit of the invention as defined in the appended claims.

What I claim is:

1. In a garment stapling apparatus, the combination of a folding board, a plurality of clincher anvils in fixed positions relatively to the board, and a stapling head swingable into staple-setting relation with each of the clincher anvils successively, and indexing means for indicating staple-setting positions of the stapling head.

2. In a garment stapling apparatus, the combination of a folding board, a plurality of clincher anvils in fixed positions relatively to the board, a stapling head swingable into staple-setting relation with each of the clincher anvils successively, and indexing means for indicating staple-setting positions of the stapling head.

3. In a garment stapling apparatus, the combination of a folding board, a plurality of clincher anvils in fixed positions relatively to the board, a stapling head swingable into staple-setting relation with each of the clincher anvils successively, and means for holding the stapling head in registration with the clincher anvil during the staple driving operation.

4. In a garment stapling apparatus, the combination of a folding board, a plurality of clincher anvils in fixed positions relatively to the board, a stapling head swingable into staple-setting relation with each of the clincher anvils successively, indexing means for indicating staple-setting positions of the stapling head, and means for holding the stapling head in registration with the clincher anvil during the staple driving operation.

5. Apparatus of the character described, comprising a folding board, a plurality of clincher anvils in fixed positions relatively to the board

and over which portions of a garment may be folded, means for releasably holding the folded portions in position over the clincher anvils, and a stapling head movable into staple-setting relation with each of said clincher anvils successively.

6. Apparatus of the character described, comprising a folding board, a plurality of clincher anvils in fixed positions relatively to the board and over which portions of a garment may be folded, a clamping arm for releasably holding certain of the folded portions in position over the clincher anvils, a second clamping arm for releasably holding other folded portions in position over said clincher anvils, and a stapling head movable into staple-setting relation with said clincher anvils.

7. Apparatus of the character described, comprising a folding board, a plurality of clincher anvils in fixed positions relatively to the board and over which portions of a garment may be

folded, a vertically swingable clamping arm for releasably holding certain of the folded portions in position over the clincher anvils, a second vertically swingable arm for releasably holding other folded portions in position over the clincher anvils, said second arm being movable independently of the first arm, resilient means acting on both arms to exert a downward pressure on said arms when they are in their depressed positions and to exert an upward pressure thereon when they are in their raised positions, and a stapling head movable into staple-setting relation with said clincher anvils.

8. Apparatus of the character described, comprising a folding board, a plurality of clincher anvils, and a stapling head, said clincher anvils and stapling head being mounted on a supporting plate which plate is detachably secured to the folding board.
